UNITED STATES PATENT OFFICE.

PAMPHILUS SCHMITZ, OF PHOENIX, ARIZONA, ASSIGNOR TO THE FRANCISCAN FATHERS OF ARIZONA, OF PHOENIX, ARIZONA, A CORPORATION OF ARIZONA.

BUILDING STRUCTURE.

1,153,714.

Specification of Letters Patent. Patented Sept. 14, 1915.

Application filed November 9, 1914. Serial No. 871,086.

To all whom it may concern:

Be it known that I, PAMPHILUS SCHMITZ, a citizen of the United States, residing at Phoenix, in the county of Maricopa and 5 State of Arizona, have invented certain new and useful Improvements in Building Structures, of which the following is a specification.

This invention relates to improvements 10 in building structures, and more particularly to improvements in the construction of hollow walls or partitions.

One of the principal objects of the invention is to provide improved means for 15 the construction of fire-proof walls or partitions having the desirable dead air spaces.

Another object of the invention is to provide a partition or wall including sheet metal studding having means for connecting 20 them to the ceiling or floor of a building, and adapted to be utilized in connection with composite concrete blocks or boards of suitable character, said studding being provided with means for maintaining and anchoring the blocks or boards in position.

A still further object is to provide a construction of the class described which will be extremely simple, durable, efficient in 25 operation, and inexpensive to manufacture.

With these and other objects in view which will become apparent as the description proceeds, the invention resides in the construction, combination and arrangement 30 of parts, hereinafter more fully described and claimed, and illustrated in the accompanying drawing, in which like characters of reference indicate like parts throughout the several figures, of which—

Figure 1 represents a side elevational view 40 of a portion of a wall or partition constructed according to my invention. Fig. 2 represents a horizontal sectional view thereof taken on the plane indicated by the line 2—2 of Fig. 1. Fig. 3 represents a fragmentary vertical sectional view taken transversely of one of the studs on the plane indicated by the line 3—3 of Fig. 2. Fig. 4 represents a fragmentary perspective view of one of the studs. Fig. 5 represents a 45 perspective view illustrating a portion of one end of one of the studs used in the construction of the outside wall, and showing the arrangement by means of which the boards or blocks are connected to said stud.

Fig. 6 represents a fragmentary horizontal

sectional view taken on the plane indicated by the line 6—6 of Fig. 5, showing the position of the blocks or boards relatively to the studs when the former are in final position.

The framework for the partitions or walls includes vertically spaced sheet metal studs 7, and ceiling and floor plates 4 and 5 respectively, (Fig. 3). The longitudinal edges of studs 7 are slotted transversely at intervals for a distance, and the tabs thus formed are bent at right angles to the stud alternately on each side thereof, to form shoulders or arms 8 against which the blocks or boards 5 are adapted to rest. The 70 shoulders occur in pairs, the members of which project on opposite sides of the stud, and the pairs of shoulders alternate with projections 9 left at the edges of the studs. Certain of the projections are somewhat 75 wider as indicated at 10 and occur at suitable intervals along the edges of each stud.

The plates or strips 4 and 5, are of a width substantially equal to the width of the studs, and are secured to the ceiling and 80 floor respectively of the building in any suitable manner, and are provided transversely at suitable intervals with slots occurring at 11 as indicated in Fig. 3. The upper and lower ends 12 and 13 respectively 85 of the studs are bent at right angles as indicated in Fig. 3, and are slipped through the slots 11 so as to lie between the plates 4 and 5 and the ceiling and floor respectively, 90 of the building. In this manner the studs 95 are maintained in vertical spaced and parallel relation.

The composite blocks or boards in being assembled are placed one above another as indicated in Figs. 1 and 2, resting at their 95 inside faces against the shoulders or arms 8, and at their ends being embraced by the projections 9 and 10 occurring along the edges of the studs. In erecting the walls or partitions joints are broken every other section 100 as indicated in Fig. 1. The distance apart between the wide projections 10 is equal to one-half the height of one of the blocks, so that the joints occur at the wide extensions 10. Both the projections 9 and 10 are provided with openings 14, the former being provided each with a single opening and the latter with a pair of openings. As the blocks are being put into position, the 105 projections 9 and 10 are strung with hori-

110

zontally extending wires 15 which are passed through the openings in the projections, and cross the blocks or boards on the outer faces thereof. For this purpose the thickness of the boards is slightly less than the length of the projections, so that the wires will lie flush with the outer faces of the boards or blocks. Transversely disposed grooves 16 may be provided at suitable intervals in each block for the reception of the wires 15. By providing the wider projections 10, and by having two wires carried by the wide projections, the adjacent ends of separate blocks forming a joint at the wide projections are suitably supported by the wires. In this manner the blocks or boards on both sides of the double wall partition are maintained in position by the co-operative action of the studs, shoulders, projections and wires, said wires lying on the outer faces of the two walls forming the hollow partition. A single coat of hard or sand finish is applied to the exposed surfaces of the partition, and serves to hide the metallic parts, as well as to eradicate the joints between the blocks. The retaining wires 15 while serving their purpose of sustaining the blocks in position also serve as anchors or keys for the outer or finishing coat.

30 In building a corner as indicated in Fig. 2, the sheet metal stud occurring at the end of one reach or arm A of the partition, indicated at 17 has certain of the shoulders 8 bent only in one direction, that is toward the adjacent stud in the same reach so that the outer face of the stud presents a flat appearance all the way across, and against said outer face the larger boards or blocks 18 are placed, the latter being equal to the width of the stud, and are maintained against said stud by the wires 15 in the same manner as previously described.

As indicated in Fig. 2 the retaining wires 15^a occurring on the inner sides of the opposite reach or arm B of the partition may be extended through the blocks 5^a occurring in the opposite arm of the partition, and passed around or secured upon the outside retaining wires of the opposite arm as at 19. This arrangement may however be dispensed with and said wires 15^a be suitably connected to the projections of the end stud 20 of the arm or reach B.

55 In constructing outside walls of a building, according to my invention, the outer edge of the studs 7^a used especially for this purpose, are as indicated in Fig. 5 provided with wings or shoulders 8^a and with the wider projections 10^a.

60 The blocks 5^b used in constructing the outer wall, are provided with transversely disposed pins or wires 21 which at their ends project slightly beyond the edges of the blocks and may be mashed over or flattened as at 22 or provided with suitable hooked

portions instead. The flattened or hooked portions 22 are adapted to engage in the bayonet slots 23 provided in the outer edges of alternate projections 10^a, and rest finally in the depressions 24 of said slots. In order that the blocks 5^b may rest in horizontal alinement when in final position, the pins or bars 21 in certain of the blocks are relatively higher than in others as indicated in Fig. 5. The distance in height between these pins is equal to the distance apart of the slots 23 of each pair. The inner edges of the studs 7^a are constructed and operate similarly to the edges of studs 7 heretofore described. This arrangement is mainly for the purpose of allowing the outside blocks to be formed to represent cut stone work or to present some other attractive appearance. The studs may be provided at suitable points with openings 25 as indicated in Fig. 4 for the reception of wiring or piping.

70 A partition constructed according to my invention will be found to be extremely strong and at the same time easy to erect. This type of partition will be found particularly useful and advantageous in cold storage rooms, cooling houses, and in fact all kinds of buildings, for the reason that it presents the advantageous dead air space between the opposite sides of the partition.

75 Although I have described the preferred embodiment of my invention, I may desire to make such changes in the construction, combination and arrangement of parts thereof as do not depart from the spirit of the invention and the scope of the appended claims.

80 I claim:

1. A partition comprising a ceiling and a floor plate adapted to be secured to the ceiling and floor respectively of a building, said plate provided with transversely disposed spaced parallel slots, flat metal studs having their opposite ends bent at right angles, said bent ends adapted to be engaged through the slots for securing said studs to the plates, said studs having their opposite edges slit for a distance to provide tabs, the tabs being bent at right angles to project on opposite sides of the studs to provide shoulders, said shoulders occurring in pairs, projections alternating with the pairs of the shoulders along the edges of said studs, certain of the projections at spaced intervals being wider than the remainder, blocks adapted to be disposed at right angles to said studs and between them and adapted to be rested against said shoulders, and retaining wires, said wires adapted to be passed through openings occurring in the outer ends of the projections to bridge the outer surfaces of the blocks, substantially as described.

85 2. A partition including vertically spaced parallel sheet metal studs, means for de-

tachably securing said studs at their opposite ends to the ceiling and floor of a building, shoulders formed on the edges of said studs and projecting on opposite sides thereof, projections forming extensions on the studs, said projections alternating with said shoulders, said projections provided with openings at their outer ends, certain of the projections at spaced intervals being wider than the remainder, blocks adapted to be disposed between said studs at right angles thereto and against said shoulders in such manner as to have the joint between the blocks occur adjacent the wider projection, and retaining means adapted to be passed through the openings in said projections whereby to bridge said blocks.

3. A stud comprising a flat metallic plate, having its opposite edges slit transversely of the plate for a distance in order to provide tabs, said tabs being bent at right angles to said plate to extend on opposite sides in order to form shoulders, said shoulders occurring in pairs alternating with unbent tabs, the latter forming projec-

tions, certain of said projections being wider than others, said projections provided at their outer ends with openings, substantially as described.

4. A partition including a plurality of spaced studs each having laterally extending shoulders provided adjacent the edges thereof and having a plurality of projections arranged in a common plane therewith, certain of the projections being wider than others, a plurality of blocks arranged between the studs and against the shoulders, with the joints between the blocks occurring adjacent the wider projections, retaining means connected with the narrower projections and extending across the blocks intermediate their ends, and retaining means connected with the wider projections and extending across the blocks adjacent their ends.

PAMPHILUS SCHMITZ.
